ROTARY PUMP PISTON

David O. Brant, Beverly Hills, Calif.

Application February 8, 1949, Serial No. 75,257

5 Claims. (Cl. 103—140)

1

This invention relates to a rotatable pump piston.

In my copending application for patent on a pump, filed January 26, 1946, Serial No. 643,613, which matured into Patent No. 2,468,734, issued May 3, 1949, I have described and claimed a pump structure of the rotary piston type comprising a two part housing one part of which is rotationally adjustable in relation to the other part in such a manner that, the outlet for the stream delivered from the pump may be reduced in size to any desired extent, even to the complete closing thereof. In said application is also described an improved rotatable piston contained in the aforesaid housing. The present application is a division of the above mentioned application and the claims hereinafter presented are confined to portions of the pump structure other than to the two part adjustable housing claimed in said copending application.

Pumps of this type now on the market are for the most part unnecessarily complicated and unnecessarily expensive to build and operate because of the metal-to-metal parts needing to be perfectly fitted to each other in order to create the required vacuum within them. Also, hitherto, their metal-to-metal engaging parts generate so much friction that they wear out more rapidly than they should, or else to reduce the friction of the rubbing part it is necessary to gear them down an undesirable amount from the speed produced by the motor, and to vary the discharge it is consequently necessary to change the gear ratio for each change of speed, or else to employ a complicated and costly variable speed drive.

Accordingly it is an object of the invention defined by the present application to provide an improved structure for the rotor per se wherein rubber or rubber-like parts may be utilized in a more advantageous way to construct the vanes or the rotor, a rotor with vanes of this kind giving a smooth operation and delivering an uninterrupted stream with a minimum of agitation of the liquid, accompanied by an absence of foaming and churning which if present might be harmful to the milk or other edible product being delivered.

A more specific object of the present invention is to provide an improved rotary pump piston wherein metal is combined with rubber or rubber-like material in such a manner that the metal weights the free end portions of the vanes of the rotor so that centrifugal force is utilized in a more efficient manner to maintain said vanes

in proper pumping contact with the inner periphery of the pump casing.

It is also an object of the present invention to provide, as a new article of manufacture, a rotor vane having an elastic body portion and an outer end portion weighted in a superior manner to aid centrifugal force.

With the foregoing and other objects in view the invention consists of certain novel parts hereinafter described and claimed, it being understood that modifications within the scope of the claims may be made without departing from the spirit of the invention.

Referring to the accompanying drawings, which illustrate what is at present deemed to be a preferred embodiment of the invention:

Fig. 1 is a plan view of the device shown attached to an electric motor wherfrom it is driven.

20 Fig. 2 is a section taken on irregular line 2—2 of Fig. 3.

Fig. 3 is a section taken on irregular line 3—3 of Fig. 2.

Fig. 4 is a section taken on angular line 4—4 of Fig. 2.

25 Fig. 5 is a view partly in section and partly in side elevation looking in the direction of the arrows 5—5 of Fig. 6.

Fig. 6 is a section taken on line 6—6 of Fig. 5.

30 Fig. 7 is an internal face view of the rotationally adjustable means for coupling the pump housing to the motor.

Fig. 8 is a vertical section on the plane indicated by line 8—8 of Fig. 2.

35 Fig. 9 is a perspective view of one of the vanes of the rotor shown in Fig. 6.

Referring in detail to the drawings, the main parts of the structure shown are the pump casing 10, motor housing 11, intermediate mounting member 12, coupling sleeve or bushing 13, rotor 14 provided with peripheral vanes 15, and the clamping means 16 whereby the pump casing 10 is fixedly secured in various rotational adjustments in relation to the motor housing 11.

40 Describing now the rotor 14 together with its vane structure, said rotor comprises a body portion 17 the general outline of which approximates a square, each corner portion of said body being furnished with an extension 18, each of said extensions having a tangentially directed, approximate semi-circular projection 19 to which is rockably attached one of the already mentioned rotor vanes 15. The rotor body 17 including its parts 18 and 19 is of the nature of 45 a thick flat plate and the vanes 15 are of sub-

stantially the same thickness as said plate, each of said vanes, as seen in side elevation being of an ovoidal shape except that it has a definite point 20 at the more tapered end of the ovoid. There is cut into that end of each vane 15 which is opposite to its point 20 an arcuate recess 21, the arc of this recess extending through somewhat more than 180 degrees, this recessed portion of the vane being rockably fitted over the aforesaid rotor extension 19 so that the vane may rock to a limited extent. In operation the rocking movement of the vane toward the center of the rotor is limited by an adjacent curved wall 22 of the rotor body, and its outward rocking movement is limited by the vane contacting with the inner face of the peripheral wall of the rotor casing.

It will be seen that the somewhat square appearance of the rotor 14 is due to the fact that its otherwise circular periphery is interrupted by circumferentially spaced apart recesses within which are swingably mounted the vanes 15, said recesses being defined principally by their curved inner sides 22 (see Fig. 3).

As well shown in Fig. 6 a spider-like reinforcing member 23 is provided for the rotor, said member consisting of a central hub portion 24 which is securable to the outer end of the motor shaft 25 and which is furnished with four radially directed arms 26, each of said arms having an arcuate tangentially directed end portion 27 which terminates in a slight globular enlargement 28 located centrally of the circular rotor extension 19. The reason for providing this spider-like reinforcement is that the rotor body is preferably made of a non-metallic material and therefore needs reinforcement.

Each of the four vanes shown is of the same size and pattern and therefore a description of one will suffice for all. Each vane is shown made of rubber or rubber-like material which, however, is sufficiently dense and form-retaining so that the attached vane may be depended upon to remain in its operative position and perform its pumping function efficiently. In order that each vane may respond more dependably to being swung out under the urge of centrifugal force, there is embedded in the point portion of each vane a metallic weight 30. These weights are triangularly shaped to conform to the point portion of the vanes and are sufficiently less in thickness than said point portion to be safely walled in by the elastic material, there being a relatively thin wall 31 between each embedded weight and the outer side of the vane carrying it.

The pump housing 10 comprises a front rotor enclosing casing 39 and, proceeding from the rotor 14 toward the motor side of the pump, a back part or closure 40, but the structure between said closure 40 and the motor housing 11 will not be described in detail in the present application, for it forms no part of the invention hereinafter claimed. It will suffice to say here that said closure 40 is rotationally adjustable about an axis which is concentric to the axis of the motor shaft 25, but is provided with a circular peripheral shoulder 42 somewhat eccentric to the axis of said motor shaft, and hence, because of said shoulder 42 fitting within the adjacent side portion of the aforesaid rotor enclosing casing 39, by rotational adjustment of said closure member 40, the outlet for the stream delivered through the discharge port 47 may be reduced in size to any desired extent, even to the complete closing thereof; and also the direction of

the flow of the liquid may be reversed. However, in all such adjustments the rotor 14 occupies the full internal diameter of the casing member 39, as shown in Figs. 2 and 3, and there is provided around said rotor a continuous, uninterrupted peripheral wall 49 against which the various vanes 15 contact under the urge of centrifugal force.

The rotor 14 is rotatably mounted upon the 10 motor drive shaft 25 by screwing a reduced threaded extremity 51 of an exposed portion of a hub 24a as seen in Fig. 5 into the threaded bore of a coupling 52, a fragmentary portion only of which is shown in Fig. 5. By referring to Fig. 15 2 it will be seen that the coupling 52 has its threaded bore also screwed onto the reduced threaded extremity of the drive shaft 25.

In operation the back wall 40 of the pump is 20 set so that the contact point of the rotor and pump housing is at the end of the discharge port 47. This setting causes the vanes 15 to push air and/or fluid out through said port and create a vacuum on the far side or intake side of the dam formed at the contact point. As air is 25 driven from the intake side liquid flows in and is pushed toward the discharge port by the vanes, thus priming the pump.

If a smaller discharge is desired and no further 30 priming is required the back wall 40 of the pump may be rotationally adjusted to bring the contact point over the discharge port, thus reducing the size of the discharge passage. Also said back wall may be so adjusted as to reverse the 35 flow through the motor, as explained in my aforementioned copending application.

The flexibility of the vanes permit them to 40 conform better to the ever changing contour of the housing and to prevent marring of the metal when grit particles get into the pump. Water and other liquids make the rubber parts slippery so that they are water lubricated just the same as rubber bearings on the propeller shafts of ships are lubricated and take care of sand particles.

It will be seen, by inspecting Fig. 6, that each 45 vane 15 has a projecting end portion 15x which is semi-circular that cooperates with a slight concave recess 15y in the peripheral portion of the rotor to limit in a stable manner the outward 50 swing of the vane.

I claim:

1. A rotary pump comprising a housing having a cylindrical interior, a rotor of non-metallic material located in and eccentric to the cylindrical interior of said housing, said rotor comprising a body portion the general outline of which approximates a polygon, a driving shaft to which said body portion is centrally secured, each corner portion of said body portion being 55 furnished with an extension hammer semi-circular projection directed tangentially in relation to the rotor considered as a whole, a plurality of peripheral vanes carried by said rotor individually having an oscillatory bearing upon said semi-circular projections and movable in a limited arc about an axis adjacent each aforesaid corner portion of the polygon, and a spider like reinforcing member located within said rotor, said member consisting of a central hub portion located centrally of the rotor and furnished with a plurality of radially directed arms, each of said arms having an arcuate end portion directed circumferentially in relation to 60 the peripheral portion of the rotor and termi- 65 70 75

nating in a globular enlargement located centrally of each said rotor projection.

2. The subject matter of claim 1 and said vanes individually having arcuately recessed attached end portions having swingable working fits upon said semi-circular rotor projections.

3. As an article of manufacture, in a structure of the kind described having a rotor chamber, a rotor body in said chamber and a rotor vane for said rotor body, said vane consisting of a non-metallic elastic body which, as seen in side elevation is of an ovate shape, said vane having a constant width such as to span the width of said chamber with a working fit in planes perpendicular to the axis of the rotor body, one end portion of said vane being contoured in its larger end portion for pivotal connection with said rotor body, said vane being tapered from its said larger end to a point located at its opposite end, said taper being in a plane extending at a right angle to the axis of the rotor body, and a metallic weight embedded in said vane adjacent to its said opposite end.

4. The subject matter of claim 3 and said weight being tapered correspondingly to said taper of said vane, and a layer of elastic material overlying the point portion of said weight.

5. As an article of manufacture, a rotor vane

consisting of a non-metallic elastic material which as seen in side elevation is of an ovate shape, the larger end portion of said ovate vane having in it a semi-circular recess, said vane being of constant width, the smaller end portion of said ovate vane being tapered to a rounded point and the tapers forming said point extending from the larger end of the vane, and a metallic weight embedded in said tapered part of the vane.
